UNITED STATES PATENT OFFICE.

FREDERICK KOHNLE, OF DAYTON, OHIO.

TYPE CHASE.

Application filed April 2, 1925. Serial No. 20,212.

To all whom it may concern:

Be it known that I, FREDERICK KOHNLE, a citizen of the United States, and residing at Dayton, in the county of Montgomery and

5 State of Ohio, have invented a new and useful Improvement in Type Chases, of which the following specification is a full disclosure.

This invention relates generally to improvements in type chases, particularly adapted for use by laymen and specifically designed for use in conjunction with price marking machines, to which the chase is adapted to be removably attached.

10 It is desirable in a chase of this character to provide means whereby each type body or character can be independently held, thereby permitting each to be conveniently and quickly interchanged or replaced without in 20 any manner disturbing the relation of the others.

It is also desirable to have each row of type independently supported and held in printing position without the use of clamping means.

25 It is further desirable to provide for the support of rows of type respectively of different "point", so that the size and, therefore, the prominence of certain lines may be obtained, when printed.

The main object of the invention is to provide a chase in which each row of type is independently supported upon an adjustable partition, and properly held between adjacent adjustable partitions or adjustable partitions and the side walls of the chase frame, the partitions adapted to be variously spaced to simultaneously receive and independently support rows of type of different 40 "point", whereby the character of printing can be changed to give more or less prominence to certain character combinations or lines conformably to printing requirements, in marking or printing upon price tags or 45 similar articles, and whereby a maximum number of spacing combinations are obtainable in a minimum area of chase opening or chase size. This object is accomplished by providing a chase having a plurality of 50 equally spaced opposingly related rows of grooves or notches and providing supporting plates or partitions, each adapted to be slidably introduced into and held in opposing grooves, all plates in parallel spaced relation, to guide, support and retain the type 55 bodies.

Another object is to provide means whereby the type can be held in the chase in rows and in proper position and spaced relation for printing, without the use of clamping 60 means.

Another object is to independently slidably support each type body in proper linearly spaced relation and thus eliminate the use of spacing slugs or like devices to prevent lateral displacement of the type in the 65 line.

Other objects and certain advantages will appear from the description of the drawings, in which:

70 Figure 1 is a top plan view of the device showing the type supporting partitions equally spaced.

Figure 2 is a vertical cross section on line 2—2 of Figure 1, showing the chase engaged 75 within its holder or support, ready for printing.

Figure 3 is a vertical longitudinal section on line 3—3 of Figure 1.

Figure 4 is a perspective view of one of 80 the type bodies.

Figure 5 is a perspective view of one of the type supporting partitions.

The chase herein is of rectangular box-like form and comprises opposite side pieces 85 1, each formed with an outwardly projecting slide or guide lug 2 adapted for engagement with correspondingly related parallel grooves 3 on the chase holder 4, which has the form of a boxing 90 attachable to the proper printing machine. Side pieces 1 are connected in parallel relation and held by end pieces 5, each of which has a series of vertical V-shaped grooves 7 therein, the width of the grooves 95 and the spacing therebetween being herein, and preferably, the same. The grooves of the end pieces are opposingly related and similar in number and spacing so that any two opposingly related grooves will receive 100 and properly dispose a single type supporting and division plate, a plurality of such plates being provided.

The grooves or slots 7 extend from what may be termed the back of the chase, only 105 partially thereacross, to form shoulders 8 for limiting the degree of insertion of a plate 9, the plate being correspondingly notched to form shoulders engageable with the slot shoulder to limit plate insertion.

110 A detail of the rectangular plate is shown in Figure 5, the same being oppositely cham-

ferred as at 10, each chamfered or knife edge portion being notched as shown at 11 to provide the above mentioned stops for limiting the insertion of the plate to bring its 5 opposite edges flush with the corresponding faces of the chase, the width of the plate being equal to the depth of the chase and its thickness, substantially equal to the width of a notch and distance between adjacent notches. The grooves 7 may be of 10 other configuration but the preferred form is shown, and the thickness of the plate is preferably very slightly less than the width of the slots and spacing between adjacent 15 slots to permit two plates to be respectively placed in adjacent pairs of grooves, thus increasing the range of adjustment to provide a maximum number of type receiving ways of various widths.

20 The distance between adjoining notches preferably corresponds to the "point" system of type body measurement, and is some multiple of the unit of measurement of that system, so that in whatever spaced relation 25 the partitions may be placed, they will receive and properly support type of corresponding "point". For example, substituting the inch system of measurement, and assuming the width of the notches and dis- 30 tance between adjacent notches to be 1/16 of an inch, the plates, herein of a width equal to the notches, may be arranged so that the distance between opposing faces of adjacent plates are respectively, 1/16, 2/16, 35 3/16, 4/16 . . . inches apart for receiving rows of type with bodies of corresponding width or "point".

Each partition is provided with a row of 40 vertically disposed parallel grooves 12 extending partially across one face of each partition and thus forming a row of linear stops 13, one for each groove, adapted to limit the movement of the type in one direction. Each type 15 has a fin 16 projecting longitudinally therefrom adapted for engagement within any groove, whereby each type body can be independently supported, and can be withdrawn without disturbing the relation of the other type of the 45 row. These ribs prevent any lateral movement of the type which are held between adjacent division plates properly spaced for printing, without the use of spacing slugs or like devices. The type, moreover, are 50 adapted to slide when brought in contact with the material to be printed, thus relieving the chase of strain which is herein transferred to and received entirely by the chase support 4, the feet of the type engaging the 55 aligning surface 20 of said support 4.

Therefore the type first engage the goods and are then simultaneously caused to slide to bring their face ends into engagement 60 with the face 20 of the chase holder, to properly align the type. The general features

and advantages of the removable type are described and claimed in my patent for type chase No. 702,323, of June 14, 1904, the feature of the invention herein being adjustability and interchangeability of the type 70 supporting partitions which enables rows of type of various point to be simultaneously set up.

Having described my invention, I claim:

1. A type chase, having opposingly related rows of spaced parallel V-shaped grooves, the width of each groove and distance between adjacent grooves being equal, and type supporting plates substantially equal in thickness to the width of a groove 80 engageable with the grooves to form parallel walled type receiving ways of different widths, whereby a maximum number of spacing combinations can be obtained in a chase of minimum size. 85

2. A rectangular open faced frame, having opposingly related similarly spaced parallel V-shaped grooves extending partially across the frame to form a series of aligned shoulders, the width of each groove and the space between adjacent grooves being equal, division plates of a width substantially equal to the widths and spacing of said shaped grooves having V-shaped ends engaged with pairs of opposingly related grooves, each plate having similarly spaced parallel rectangular grooves extending partially across the plate to form a series of aligned shoulders, the grooves adapted to receive a projection of a type body for supporting the type at one side, said plates adjustable to form type receiving ways of varying widths 100 therebetween. 95

3. A type chase providing oppositely related rows of spaced parallel grooves, the spacing and widths of the grooves being equal, and type supporting division plates substantially equal in thickness to the spacing and widths of the grooves engageable with any opposite related grooves for spacing adjacent plates to provide type receiving ways of different widths. 105

4. A type frame of rectangular configuration having opposingly related rows of equally spaced parallel grooves with the widths of the grooves equal to the spacing therebetween, and type supporting division plates each of the thickness substantially equal to the width and spacing of the grooves, engageable with the grooves to form ways for respectively supporting rows of type of different width or point. 115

5. A type chase comprising a frame of rectangular configuration having in each of two opposite parallel sides a series of similarly spaced grooves with the width of the grooves equal to the space between the grooves, and rectangular partition plates of a thickness substantially equal to the grooves and spacing therebetween, engageable with 120 125 130

oppositely related grooves to dispose the plate in parallel relation to the side of the frame or to a similar adjacent plate to form a type receiving way, or ways, each plate 5 having spaced shoulder grooves adapted to receive a projection of a type body to support and secure the same in printing position between adjacent plates.

6. A rectangular type chase having opposingly similarly spaced parallel rows of 10 grooves the width of the grooves and the spacing therebetween being equal, and each groove having a stop shoulder and type sup-

porting division plates engageable within any pair of opposingly related grooves to 15 form type receiving ways of different widths, and to obtain a maximum number of spacing combinations in a chase of minimum size, each plate having a series of equally spaced grooves in one face parallel with the first 20 mentioned grooves adapted to receive a projection of a type body for supporting the type between adjacent plates.

In witness whereof, I hereunto subscribe my name.

FREDERICK KOHNLE.
